UNITED STATES PATENT OFFICE.

WILLIAM H. MATTHIES, OF HACKENSACK, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,362,126.

Specification of Letters Patent. Patented Dec. 14, 1920.

Application filed February 20, 1917. Serial No. 149,789.

To all whom it may concern:

Be it known that I, WILLIAM H. MATTHIES, a citizen of the United States, residing at Hackensack, in the county of Bergen and 5 State of New Jersey, have invented certain new and useful Improvements in Telephone Systems, of which the following is a full, clear, concise, and exact description.

This invention relates to the control of 10 signaling means, and more particularly to signaling means employed in telephone systems.

In semiautomatic telephone systems, especially on calls from a semiautomatic to 15 a manual office, it is necessary to indicate to the B operator the number of the called subscriber's line. In the present practice, it is customary to indicate the number of the called subscriber by the display of properly arranged lamps before said B operator. The lighting of these lamps is controlled by a sending device operated by the answering or A operator. In the operation of this 20 number-indicating or displaying means, it is essential that the number be not erased until the B operator has disposed of the call, and until the number-indicating means has been placed in condition to receive another call.

30 The main feature of this invention resides in the provision of means to associate a set of signaling lamps with the trunk on which the next call is awaiting before the preceding call has been disposed of, and means to prevent the operation of such signals before the number of the preceding call indicated thereby has been erased.

The present invention is designed primarily for use in a telephone system which 40 serves to complete connections from a calling line terminating at a semimechanical exchange to a called line terminating at a manual exchange, although the present invention is not limited to this particular use.

45 In the operation of such a system, the calling subscriber in initiating a call lights a line lamp at the A operator's position at a semimechanical exchange. The A operator is thereupon connected to the calling line and ascertains the number of the wanted 50 line and then proceeds to set one or more automatic switches which serve to connect her position with the B operator's position at the wanted exchange over a selected trunk.

55 As soon as the A operator's position has

been extended to the B operator's position a trunk finder previously allotted, connects the circuits of its associated sets of indicators to the selected trunk. The allotted set of indicators is then operated over the selected trunk by impulses from a sender selectively controlled by the A operator. It will of course be understood that other connections may be simultaneously established and that sets of indicators associated with other trunk finders may be simultaneously operated. At each B operator's position there is provided one set of lamps for indicating the wanted number and coöperating in the control of these lamps there are seven sets of the mentioned indicators any one of which sets when operated may be associated under the control of a lamp allotter or distributor with this set of lamps. It is the purpose of the present invention to associate the set of lamps with another set of operated indicators while the set of lamps are already lighted and means are provided to prevent a second designation on the lamps until the station indicated has been called and the lamps extinguished.

The drawings, with Figure 1 placed above Fig. 2, and Fig. 2 placed above Fig. 3, diagrammatically represent a portion of a telephone system employing the present invention. Fig. 1 diagrammatically represents indicators or circuit-controlling devices for the number lamps. Fig. 2 diagrammatically represents a trunk finder, an allotter for allotting any one of a plurality of trunk finders for use, and a lamp allotter for associating a set of number lamps with a trunk on which a call has originated. Fig. 3 diagrammatically represents a B operator's cord circuit and the means for automatically selecting ringing current. At the left-hand side of Fig. 3 there is diagrammatically shown an A operator's position and an impulse sending device associated therewith.

Within the dotted rectangle at the extreme right of Fig. 2, there is indicated an allotter. This allotter is common to a plurality of trunk finders and operates to select an idle trunk finder to care for the next call that is originated. At the left of this allotter there is a second dotted rectangle within which is indicated the apparatus individual to a lamp allotter. This lamp allotter is also common to a plurality of trunk finders and operates to associate a set of num-

ber displaying lamps with a trunk on which a call has originated. In former systems this lamp allotter or selector did not associate a set of lamps with a second trunk on which a call was awaiting attention until the operator had completed the connection for the first call and until the number of the first call as displayed by the set of lamps had been erased.

10 The indicators, allotters and sequence switches employed in the system are similar in structure to the sequence switch disclosed in Reynolds-Baldwin Patent No. 1,127,808, and are similar in operation and function 15 to the sequence switches disclosed in Mc-Berty Patent No. 1,125,579.

The trunk finder of this system is similar to the selecting switch disclosed in Craft-Reynolds Patent No. 1,123,696 and may be 20 controlled by circuits disposed in patent 25 to Lundell No. 1,168,319, January 8, 1916.

In this description reference will be made to a fundamental circuit. This fundamental circuit, it will be understood, connects 25 with the trunk terminals as shown at the left of Fig. 3, and includes a stepping relay 389 which actuates counting devices under the control of registers (not shown) set by an A operator in initiating a call. A complete disclosure of the fundamental circuit, 30 of the stepping relay and registers will be found in the patent to Lundell, No. 1,168,- 319, above mentioned.

When the A operator has received the 35 number of the wanted line from the calling subscriber, she proceeds to set a selector switch the brushes of which are indicated at 376 and 377 to connect her position with the position of the B operator at the wanted exchange. The A operator thereupon 40 depresses key 383 to connect her sending device to the selected trunk. The depression of key 383 causes the sequence switch 385 to rotate into position 11, in which position 45 the sender is connected through contacts 378 and 381 to the selected trunk. In the meantime the sender may be adjusted to store up the designation of the wanted line.

When the A operator's position has been 50 connected to the B operator's position over the trunks 303 and 305, the fundamental circuit is extended to the line relay 306. This circuit may be traced from grounded 55 battery, contact 307, winding of line relay 306, contact 308, trunk 303, terminal 302, brush 376, contact 381, stepping relay 389, contacts 390, 387 and 378, brush 377, terminal 304, trunk 305, contact 309, to ground. The line relay 306 attracts its armatures 60 and at its right-hand armature and front contact, completes a circuit from ground, contact 310, magnet of sequence switch 300, to grounded battery, to move sequence switch 300 into position 2. With the sequence switch 300 in position 2, a relay 201

(Fig. 2) is energized over a circuit extending from grounded battery, winding of relay 201, contacts 202, 203, 311, to ground. The relay 201 attracts its armatures and at its right-hand armature and front contact 70 completes a circuit from ground through contacts 204, 205, magnet of sequence switch 200, to grounded battery, to move the sequence switch into position 2. As soon as the sequence switch 200 rotates 75 through position 1½, the relay 201 is energized over a circuit now traced from grounded battery, winding of relay 201, contacts 202, 209, resistance, back contact and armature of relay 210 to ground. In 80 position 2 of the sequence switch, an operating circuit for the updrive magnet 206 is closed from grounded battery, winding of up-drive magnet 206, conductor 207, contact 208, right-hand front contact and armature of relay 201 to ground. The trunk 85 finder switch, designated as 212, elevates its brushes under the control of the up-drive magnet 206. As soon as the trunk finder 212 has positioned its brushes on the terminals of the trunk on which a call has been initiated, the relay 210 is energized over a circuit from grounded battery, winding of relay 210, contacts 213, 214, 215, 216, brush 217, terminal 218, conductor 219, contact 90 312 to ground. If, however, the brushes of the trunk finder 212 have not been properly centered on the selected set of terminals, the relay 201 is maintained energized over a circuit established from grounded 100 battery, winding of relay 201, left-hand contact and armature of this relay, conductor 220, contact 221, conducting portion of commutator 222, brush 223, to ground. When, however, the brushes of the trunk 105 finder have been accurately centered on the selected set of terminals, the brush 223 rests on an insulating segment of commutator 222 and the relay 201 deenergizes, completing at its right-hand armature and back 110 contact a circuit from ground through contact 224, magnet of sequence switch 200 to grounded battery, to move the sequence switch into position 3. With the sequence 115 switch 200 in position 3 and with the relay 210 energized, a circuit is completed for moving sequence switch 300 out of position 2 and into position 3. This circuit may be traced from grounded battery, magnet of sequence switch 300, contacts 312', 313, conductor 314, terminal 225, brush 226, conductor 227, contacts 228, 214, front contact and armature of relay 210 to ground. When 120 the sequence switch 300 moves out of position 2, the relay 306 is maintained energized 125 over a circuit now closed from grounded battery, contact 307, winding of relay 306, contact 315, left-hand armature and front contact of relay 306, contacts 316, 317, over the fundamental circuit previously described, to 130

ground at contact 309. The relay 201 now has its energizing circuit completed from grounded battery, winding of relay 201, contacts 202, 230, brush 231, terminal 232, conductor 233, contacts 318, 319, right-hand front contact and armature of relay 306, to ground. With relay 201 energized a circuit is completed from grounded battery, magnet of sequence switch 200, contacts 205 and 204, right-hand front contact and armature of relay 201 to ground, for moving this sequence switch into position 4.

A circuit for indicator 100 is now completed from grounded battery, magnet of indicator 100, contact 111, conductor 142, contact 243, conductor 220, left-hand armature and front contact of relay 201, contacts 202, 230, brush 231, terminal 232, conductor 233, contacts 318, 319, right-hand front contact and armature of relay 306 to ground. As the indicator 100 rotates through its various positions, it operates the contact 109. Each time that the contact 109 is closed, a circuit for shunting the stepping relay is completed from grounded battery, contact 307, winding of relay 306, contact 315, left-hand armature and contact of relay 306, contacts 316 and 320, conductor 321, terminal 234, brush 235, conductor 236, conductor 112, contact 109, conductor 110, contact 242, right-hand front contact and armature of relay 201 to ground. The indicator 100 continues to rotate thereby shunting the stepping relay until the series of counting relays (not shown) has been energized. The 0 counting relay of the series of counting relays mentioned operates to interrupt the fundamental circuit, thereby causing the relay 306 to deenergize. When relay 306 deenergizes, the relay 201 has its energizing circuit interrupted at the right-hand front contact and armature of relay 306. The relay 201 retracts its armatures, and a circuit is closed for moving the sequence switch 200 out of position 4. This circuit may be traced from grounded battery, magnet of sequence switch 200, contact 244, conductor 245, contacts 113, 114, 115, 116, 117, 118, conductor 120, contact 246, conductor 247, right-hand back contact and armature of relay 201 to ground.

In the operation of the sender the fundamental circuit is again closed from grounded battery, contact 307, winding of relay 306, contacts 315, 322, 323, conductor 241, terminal 240, brush 239, conductor 238, contact 248, conductor 249, contacts 127, 106, 105, 104, 103, 102, 101, conductor 236, brush 235, terminal 234, conductor 321, contacts 320 and 317, trunk 303, terminal 302, over the fundamental circuit mentioned to terminal 304, trunk 305, contact 309 to ground. The relay 306 attracts its armatures, and at its right-hand armature completes a circuit from ground, right-hand

armature and front contact of relay 306, contacts 319, 318, conductor 233, terminal 232, brush 231, contacts 230, 202, winding of relay 201, to grounded battery.

In position 5 of sequence switch 200, a circuit is completed for the indicator 122, which circuit may be traced from grounded battery, magnet of indicator 122, contact 123, conductor 124, contact 250, conductor 220, left-hand armature and front contact of relay 201, contacts 202, 230, brush 231, terminal 232, conductor 233, contacts 318, 319, right-hand front contact and armature of relay 306 to ground.

As the indicator 122 rotates through its various positions, it closes its contact 125. At this time the contact 125 closes a circuit in shunt of the fundamental circuit which circuit is completed from grounded battery, contact 307, winding of relay 306, contact 315, left-hand armature and front contact of relay 306, contacts 316, 320, conductor 321, terminal 234, brush 235, conductors 236, 112, contact 125, conductor 110, contact 242, right-hand front contact and armature of relay 201, to ground. The indicator 122 continues to rotate and to operate its contact 125 until a sufficient number of impulses are transmitted to the stepping relay to actuate a series of counting relays, the number of which is determined by the setting of the register mentioned but not shown. When the series of counting relays has been actuated, the fundamental circuit is again interrupted to cause the deenergization of the line relay 306. When the line relay 306 deenergizes, the relay 201, as previously described, has its operating circuit interrupted at the right-hand front contact and armature of the relay 306. When the relay 201 retracts its armatures, a circuit is completed for moving the sequence switch 200 out of position 5 and into position 6. This circuit is established from grounded battery, magnet of sequence switch 200, contact 251, conductor 252, contacts 126, 115, 116, 117, 118, conductor 120, contact 246, conductor 247, right-hand back contact and armature of relay 201 to ground. The indicators 127, 128, 129, 130 are successively operated in the same manner as described in the operation of indicators 100 and 122.

The manner of setting the indicators 127, 128, 129 and 130 will be readily understood from the setting of indicator 100, and therefore it has not been deemed necessary to describe these operations. These operations, however, are fully described in the allowed application of F. N. Reeves, Serial No. 200,058, filed November 3, 1917, issued as Patent No. 1,337,482, April 20, 1920. The setting of the various indicators controls the actuation of the series of sets of lamps of which set 139 is a part, which series indicate the digits of the desired number.

The set of lamps is arranged to be actuated through the contacts 140 and 141 of indicators 100 and 122 or through the contacts 140' and 141' inclosed within the dotted 5 rectangle and controlled by other indicators similar to 100 and 122.

It will be understood that the fundamental circuit is completed and that the relays 306 and 201 are energized during the operation of each of these indicators. At the 10 close of the operation of each indicator, the fundamental circuit is interrupted as described, and the relays 306 and 201 deenergize. Each time the relay 201 deenergizes, 15 the sequence switch 200 is advanced one position. At the close of the setting of the indicators, the relays 201 and 306 will be deenergized, sequence switch 300 will be in position 3 and sequence switch 200 will be 20 in position 9.

The sequence switch 300 will then be moved out of position 3 and into position 4 over a circuit extending from grounded battery, magnet of sequence switch 300, contacts 312' and 357, conductor 346, terminal 280, brush 281, conductor 283, contact 134, conductor 120, contact 246, conductor 247, right-hand back contact and armature of relay 201, to ground.

30 The relay 330 is energized at this time over a circuit completed from grounded battery, contacts 331, 332, winding of relay 330, trunk conductor 303, terminal 302 to ground at a preceding automatic switch 35 through brush 376 and contact 380. Relay 330 attracts its armature, and while the sequence switch 300 is in position 4 and when it is rotating through position 5, a circuit is completed from grounded battery, 40 contact 333, front contact and armature of relay 330, contacts 334, 335, conductor 336, left-hand winding of relay 337, to ground. The relay 337 attracts its armatures and at its right-hand armature and front contact 45 completes a circuit from ground, contacts 313, 338, right-hand winding of relay 337, contact 339, to grounded battery. Relay 337 is maintained energized in this circuit until the sequence switch 300 moves 50 out of position 7. At the right-hand armature and front contact of relay 337, a circuit is also completed from ground through conductor 314, terminal 225, brush 226, conductor 227, contacts 228, 213, winding of relay 55 210 to grounded battery. The relay 210 attracts its armature and thereby completes a circuit from ground, armature and front contact of relay 210, contact 253, magnet of sequence switch 200, to grounded battery. 60 The circuit operates to move the sequence switch 200 out of position 9 and into position 10.

As soon as the sequence switch 200 leaves position 9, the energizing circuit of relay 65 210 is interrupted at the contact 213. In

position 10 the relay 201 is energized over a circuit extending from grounded battery, winding of relay 201, contacts 254, 228, conductor 227, brush 226, terminal 225, conductor 314, right-hand armature and front contact of relay 337 to ground. As soon as the relay 210 deenergizes, a circuit is completed from grounded battery, magnet of sequence switch 200, contact 255, back contact and armature of relay 210 to ground, 70 to move the sequence switch 200 out of position 10 and into position 11. Relay 201 is then locked up over a circuit completed through its left-hand front contact and armature, conductor 220, contact 297, conductor 227, brush 226, terminal 225, conductor 314, right-hand armature and contact of relay 337 to ground. Relay 201 is thus locked up until the operator has plugged into the jack of the wanted line.

85 As soon as the sequence switch 200 reaches position 10, the relay 256 which controls the setting of lamp allotter 261 is energized over a circuit established from grounded battery, winding of relay 256, contact 257, conductor 258, resistance 259, contact 260, conductor 220, left-hand armature and front contact of relay 201, contacts 254, 228, conductor 227, brush 226, terminal 225, conductor 314, right-hand armature and front contact 90 of relay 337 to ground. Relay 256 attracts its armature and at its back contact opens a break-point in the operating circuit of the lamp allotter 261. The relay 256 is maintained energized until the sequence switch 95 200 rotates out of position 14.

With the sequence switch 200 in position 11, and with relay 201 energized, a circuit will be completed for energizing the relay 210. This circuit may be traced from 105 grounded battery, winding of the relay 210, contacts 267, 268 and 269, back contact and armature of relay 264, front contact and armature of relay 256, through front contact and armature of relay 201 to ground. The relay 210 attracts its armature and thereby completes a circuit from ground, armature and front contact of relay 210, contact 253, magnet of sequence switch 200, to grounded battery, for moving the sequence switch 200 110 out of position 11. As soon as the sequence switch 200 reaches position 12, relay 264 is energized over a circuit extending from grounded battery, winding of relay 264, conductor 265, contact 131, conductor 145, contact 266 to ground. Relay 264 attracts its armature, which permits the lamp allotter to associate the set of lamps with the next trunk to be served, but renders the circuits 115 inoperative until the preceding call has been 120 erased. When the relay 264 attracted its armature, it interrupted at its back contact the energizing circuit of the relay 210, causing this relay to deenergize and retract its armature. A circuit is thus completed from 125 130

ground, armature and back contact of relay 210, contact 255, magnet of sequence switch 200 to grounded battery, to move the sequence switch out of position 12 into position 15. While the sequence switch 200 is rotated through position 14 and into position 15, the number of the called subscriber is displayed by means of the lamp signals in accordance with the set position of the 10 number indicators in the manner which is fully set forth in the above-mentioned Patent No. 1,337,482.

When the sequence switch 200 is rotated through position 14 into position 15, an 15 energizing circuit of the relay 324 was also completed from grounded battery, contact 325, winding of relay 324, contacts 326, 318, conductor 233, contact 232, terminal 231, contacts 230 and 209, through the resistance, back contact and armature of relay 210 to ground. Relay 324 attracts its armatures and completes a circuit from grounded battery, left-hand armature and front contact of relay 324, contact spring 327, contact 328, winding of relay 306, contact 329 to ground. At the right-hand armature and front contact of relay 306, a circuit is closed from ground, contact 310, magnet of sequence switch 300 to grounded battery, to 25 move the sequence switch out of position 4. Sequence switch 300 continues to rotate under the control of its master contact 301 until it reaches position 7. With the relay 306 energized and while the sequence 30 switch 300 is rotating through positions 5 to 8, the relay 330 is energized over a circuit completed from grounded battery, contacts 331 and 322, left-hand armature and front contact of relay 306, contacts 316 and 347, winding of relay 330, trunk conductor 303, terminal 302, brush 376, and contact 380 to ground.

When the B operator inserts the plug 341 into the jack of the called line, relay 342 is 45 energized, and with sequence switch 300 in position 7, a circuit is closed from ground, lower armature and front contact of relay 342, left-hand armature and front contact of relay 337, conductor 343, contact 344, magnet of sequence switch 300 to grounded battery, for moving the sequence switch into position 8. As soon as the sequence switch 300 moves out of position 7, the locking circuit of the relay 337 is interrupted at the 55 contacts 313, 338 and 339, causing this relay to open the energizing circuit of relay 201.

In position 8 of sequence switch 300, ring- 60 ing current is applied as follows: Relay 349 is energized over a circuit which may be traced from ground, lower armature and front contact of relay 342, left-hand armature and back contact of relay 337, conductor 358, armature and back contact of relay 359, back contact and upper armature of relay 350, winding of relay 349, conductor 351,

contacts 352 and 353, armature and front contact of relay 330, contact 333 to grounded battery. Relay 349 attracts its armatures to apply ringing current through the winding of relay 359, contact 360, lower armature 70 and front contact of relay 349, through the ring of plug 341, through the substation apparatus, tip of plug 341, upper front contact and armature of relay 342, upper front contact and armature of relay 349, contact 75 361 to ground. Relay 359 is marginal and does not attract its armature until the called subscriber has removed his receiver from the switchhook. Relay 359 thereupon attracts its armature and removes the shunt 80 around relay 350. Relay 350 attracts its armatures and establishes a locking circuit for itself through its upper front contact and armature. This locking circuit, which also serves to short-circuit the relay 349, may be 85 traced from ground, lower armature and front contact of relay 342, conductor 353, left-hand armature and back contact of relay 337, conductor 358, winding of relay 350, upper armature and front contact of this 90 relay, conductor 351 to grounded battery, at contact 333. The relay 350 is maintained energized over this circuit during conversation, and the relay 349 is short-circuited, causing it to retract its armatures, and the 95 calling subscriber at this time is connected to the called substation.

As soon as the relay 201 deenergized when its locking circuit was interrupted at the right-hand armature and contact of relay 100 337, when the operator plugged into the jack of the wanted line, a circuit was closed from ground, right-hand armature and back contact of relay 201, contact 224, magnet of sequence switch 200 to grounded battery, to 105 move this sequence switch into position 16.

As soon as the sequence switch 200 moves out of position 15, the indicator 100 is restored to its normal position over a circuit completed from grounded battery, magnet 110 of indicator 100, contact 135, conductor 136, contact 285, conductor 247, right-hand back contact and armature of relay 201 to ground. The indicator 122 is similarly restored over a circuit completed, through contact 286. 115 The indicator 127 is restored to its normal position over a circuit established from grounded battery, magnet of the indicator 127, contact 137, conductor 138, contact 287, to ground. The indicators 128, 129, 139 are 120 restored over similar circuits completed through contacts 288, 289 and 290.

As soon as indicator 122 rotates through position 4, the energizing circuit of relay 125 264 is interrupted at contact 131 for rendering effective the circuits of the preselected set of indicators.

In position 16 an energizing circuit is also completed for down-drive magnet 270, which circuit may be traced from grounded bat- 130

tery, winding of magnet 270, contact 271, to ground. Under the control of the down-drive magnet 270, the trunk finder switch 212 is restored to its normal position, and 5 when commutator brush 272 engages the normal conducting segment 273, a circuit is completed from ground, through commutator brush 272, segment 273, conductor 274, contact 275, magnet of sequence switch 200, to 10 grounded battery, to move the sequence switch into position 17.

In position 17 a circuit is completed for moving the sequence switch 200 into position 18. This circuit is established from grounded battery, magnet of sequence switch 200, contact 276, conductor 277, contacts 132, 114, 115, 116, 117, 118, conductor 120, contact 246, conductor 247, right-hand back contact and armature of relay 201 to ground.

20 At the termination of the conversation the operator depresses key 383 which causes the sequence switch 385 to move into position 1. The energizing circuit of relay 330 is interrupted at contact 380 and this relay 25 on retracting its armature causes the deenergization of relay 324 and this in turn causes relay 306 to be deenergized. The relay 306 retracts its armatures and thereby 30 closes a circuit from ground, its right-hand armature and back contact, contact 355, magnet of sequence switch 300 to grounded battery, to move this sequence switch into position 9. In position 9 the disconnect lamp 362 is lighted in a circuit which may 35 be traced from grounded battery, the lamp 362, contact 363 to ground. The operator on noting the signal 362 removes the plug 341 from the jack of the called line. Relay 342 retracts its armatures and thus completes a 40 circuit from ground, lower armature and back contact of relay 342, contact 364, magnet of sequence switch 300 to grounded battery. The sequence switch 300 now moves into normal position and the apparatus is in 45 readiness for the next call.

It will be understood that the trunk finder allotter 298 operates to select a trunk finder and its associated set of indicators for use with any trunk on which a call is 50 waiting. As soon as the sequence switch associated with the trunk finder in use has arrived in some position between 4 and 17, the trunk finder allotter 298 will be operated over a circuit extended from grounded 55 battery, magnet of the trunk finder allotter 298, contacts 299 and 296 to ground. Under the control of this circuit, the trunk finder allotter rotates into position to select the next trunk finder to be used. The sequence 60 switch of this trunk finder will be standing in position 18 and will be moved into position 1 over a circuit similar to the following: grounded battery, magnet of sequence switch 200, contacts 205 and 296, through 65 the master contact of the trunk finder allot-

ter to ground. Since the operation of an allotter of this type is well known and since it is also described in the mentioned application of F. N. Reeves it need not be further described.

70 What is claimed is:

1. In combination, a selectively operable number indicating device, a plurality of switches, means for operating said switches to actuate said indicating device, mechanism for associating said switches with said indicating device for controlling the same, means for causing said mechanism to associate a switch with said indicating device while another switch is actuating the same, and means for rendering effective the control of only one of said switches.

2. In combination, a selectively operable signal, a plurality of switches for controlling the operation of said signal, a plurality of controlling circuits, a finder for each of said switches arranged to connect an associated switch to any one of said controlling circuits, mechanism for associating switches with said signal for controlling the same, an allotter controlled at said finder for causing said mechanism to associate a switch with said signal while another switch is actuating the same, and means for preventing the actuation of said signal by more than one switch at any time.

3. In combination, an electric signal, two actuating circuits therefor, a pair of switching devices for controlling each of said circuits, means controlled at a distant point for operating one pair of switching devices, other means controllable at a distant point for operating the other pair of switches, an allotter coöperating in the control of one switching device in each pair, means for causing said allotter to preselect one pair of switching devices while another pair of switching devices is in operation, and means controlled by said allotter for preventing the operation of the last mentioned pair of switching devices until the first pair has completed its operation.

4. In combination, a signal, a plurality of switches arranged to actuate the same, a lamp allotter having a plurality of positions and controlling in its various positions the operation of the switches, means controlled at any one of said switches for moving said allotter into a position permitting the operation of the last-mentioned switch, means effective during the operation of the first switch to cause said lamp allotter to preselect another switch for use, and means operative thereupon for rendering said last mentioned switch ineffective until said first mentioned switch successfully completes its operation.

5. In combination, a signal, a plurality of selectively operable switching devices each

arranged to control said signal, separate means controllable at a distant point for operating said devices, a sequence switch for each of said devices arranged to coöperate in their control, an allotter having a plurality of operating positions, means under the joint control of any one of said sequence switches and said allotter for causing one of said devices to actuate said signal, means to cause said allotter to preselect a second switching device while another is in operation, and means controlled by said actuated device for preventing the mentioned coöperation of allotter and the sequence switch of the preselected switching device.

6. In combination, an operator's position, a trunk over which a call is to be extended from said operator's position, a second operator's position to which said trunk may be connected, finder switches, one of which is operable to engage terminals of said trunk, a selectively operable number indicating device, a plurality of switches for controlling the operation of said device, means

controlled from the first named operator's position for operating said switches, means effective during the operation of one of said switches to preselect another switch for use, and means operable thereupon for rendering the last named switch ineffective until the first named switch has performed its operation.

7. In combination, a selectively operable number indicating device, a plurality of switches, means controlled from a distant point for selectively operating said switches to control said indicating device, mechanism for operatively associating said switches with said signal to control the same, means for causing said mechanism to associate a switch with said indicating device while another switch is actuating the same, and means for rendering effective the control of only one of said switches.

In witness whereof, I hereunto subscribe my name this 19th day of February A. D., 1917.

WILLIAM H. MATTHIES.
